Primary Examiner—Robin V. Taylor*(74) Attorney, Agent, or Firm*—Goldstein Law Offices P.C(57) **CLAIM**

The ornamental design for a paint bucket divider, as shown and described.

DESCRIPTION

FIG. 1 is a perspective view of a paint bucket divider.

FIG. 2 is an alternate perspective view of the paint bucket divider.

FIG. 3 is a top plan view of the paint bucket divider.

FIG. 4 is a bottom plan view thereof.

FIG. 5 is a left side elevational view thereof, the right side elevational view being a mirror image of the left side view.

FIG. 6 is a rear elevational view thereof; and,

FIG. 7 is a front elevational view thereof.
